UNITED STATES PATENT OFFICE.

THOMAS LONET, OF OAKLAND, CALIFORNIA.

DESIGN FOR A COMBINATION AUTOMOBILE LIGHT.

Application filed March 19, 1923. Serial No. 5,535. Term of patent 14 years.

To all whom it may concern:

Be it known that I, THOMAS LONET, a citizen of the United States, residing at Oakland, in the county of Alameda and State of California, have invented a new, original, and ornamental Design for a Combination Automobile Light, of which the following is a specification, reference being had to the accompanying drawing, forming a part thereof.

Figure 1 is a front elevation of the improved light.

Figure 2 is an edge elevation of the same.

I claim:

The ornamental design for a combination automobile light, as shown.

THOMAS LONET.
